UNITED STATES PATENT OFFICE.

AMOS WELAND, OF WALFORD, IOWA.

STEEL FENCE POST.

Application filed January 2, 1926. Serial No. 79,041.

This invention relates to fence-posts formed of rolled steel, diversely flanged for stiffness in all directions, and commonly provided with an anchor-plate to impart stability in the ground.

The object of this invention is to improve the construction of fence-posts of this type so as to produce a strong and stable post, and one specially adapted for convenience in attaching and detaching the fence wires.

The invention is fully disclosed in the description and claims following, reference being had to the accompanying drawing, in which:—

15 Fig. 1 is a side elevation of a post embodying the invention, with a fragment of woven wire fencing material attached. Fig. 2 is a side view of the post on an enlarged scale, broken midway of its length.

20 In the drawing, the numeral 5 denotes a fragment of woven wire fencing, of a familiar type. The various spacing of the strand wires in such fencing necessitates a rather close spacing of the points of attachment with the post, so as to avoid undue deflection of the wires. Otherwise, as for supporting separate barbed wires, for example, the spacing might be much more open, and with comparatively few points of attachment.

25 The post 6 is designed for both type of wire fence, and the wire spaces are accordingly numerous and rather close together. The post itself is primarily a length of T-bar steel, provided with an attached anchor-plate 7, and is adapted to be driven

30 into the earth in the usual way.

In the flange or rib of the post which projects toward the fence-wires, and designated by the character 6^a, is punched a series of 35 slot-like notches or recesses 8. These are adapted to receive the fence wires, which are locked in position by a single flat bar 9 suitably fastened to the side of the slotted flange. In practice a strip of steel $1/8'' \times 1/2''$ serves 40 every purpose, and but few fastenings to the post are required. Holes 10 are punched in the post, and corresponding holes 11 in the bar. The preferred fastenings at all points, except the lower end, are bolts 12, though a 45 looped and twisted wire 13 answers the purpose very well. For the lower end of the bar

it is preferred to provide the post with a lateral stud 14, permanently attached to the post, and slot the hole at the lower end of the bar, so that it may engage the stud as a hook, 55 for convenience in erecting the fence.

The posts being set, the building of the fence is a very simple operation and quickly done. A free end of the fence material is first secured to a terminal post. Then as the 60 fence wire is unrolled it may be attached to posts successively by dropping the wires into the recesses therein. To counteract any tendency on the part of the fence wire to spring out of the recesses, they are preferably inclined downwardly as shown, so that gravity tends to keep the wires in place. The hooked end of the bar being now attached to the stud outside the bottom wire, it is a very simple matter to swing the bar up to its final 65 position and fasten it there, thus locking the whole series of fence wires in position at once.

To detach the fence from the posts is quite 70 as easy, if the bolts have not rusted too much in the meantime. If the nuts do not turn off easily, they are quickly knocked off with a cold-chisel, the bars detached, and the fence stripped off bodily.

The notching of the edge of the flange of 75 course tends to weaken the post laterally, but the attached metal strip, crossing the slots, acts as a truss member when securely fastened to the post, and gives it practically the strength of the originally unpunched bar. 80

Having thus described my invention, I 85 claim:

1. A fence-post, comprising a flanged metal body provided with a series of recesses extending inwardly from the edge of a flange, 90 all inclining downwardly from their outer opening, a stud attached to the flange near the ground line, and a fastening metal strip secured to the side of the flange across the recesses, outside their bottoms, to hold the 95 fence-wires in place, one end of the strip being formed as a hook to engage said stud.

2. A fence-post comprising a flanged body, one flange being provided with a series of recesses extending inwardly from the outer 100 edge of the flange, and all inclined downwardly, and a fastening strip secured to the

side of the flange along the notched margin and outside the bottoms of the recesses, to hold the fence wires in position.

3. A fence-post, comprising a flanged metal body provided with a series of recesses, all downwardly and inwardly inclined from the edge of a flange also pierced with

intermediate holes, and a metal fastening strip pierced to register with the holes in the flange, and when in fastening position disposed with its inner edge outside the fence wires seated in said recesses. 10

In testimony whereof I affix my signature.

AMOS WELAND.
